UNITED STATES PATENT OFFICE

JACOB F. LANGBEIN, OF HAMDEN, CONNECTICUT, ASSIGNOR TO THE NEW HAVEN CLOCK COMPANY, OF NEW HAVEN, CONNECTICUT, A CORPORATION

CLOCK

Application filed April 14, 1930. Serial No. 443,977.

This invention relates to an improvement in clocks and particularly to clocks designed for use upon automobiles, though not so limited.

- 5 The main object of this invention is to produce, at a low cost for manufacture, a clock having simple and effective winding-means constructed with particular reference to convenience of use.
- 10 With the above and other objects in view, as will appear from the following, my invention consists in a clock characterized by its provision with a manually-operable flexible pull-cord, or equivalent, connected to the driving-spring thereof for winding the same, and spring-means separate and distinct from the said pull-cord for returning the same to its normal position when released from manual restraint.
- 15 My invention further consists in a clock characterized as above and having certain details of construction and combinations of parts as will be hereinafter described and particularly recited in the claims.
- 20 In the accompanying drawings:

Fig. 1 is a view in front elevation of a clock embodying my invention;

Fig. 2 is a view in rear elevation of the movement-unit thereof with a portion of the case shown in section;

Fig. 3 is a view thereof in side elevation;

Fig. 4 is a view of the movement-unit in rear elevation corresponding to Fig. 2, but with the winding-drum and return-spring removed;

Fig. 5 is a broken detail sectional view through the winding-drum and associated parts taken on the line 5—5 of Fig. 2; and

Fig. 6 is a broken detail sectional view of the driving-spring and associated parts taken on the line 6—6 of Fig. 4.

In the particular embodiment of my invention herein chosen for illustration, I employ a winding-drum 10 formed in its periphery with a shallow groove 11 and

mounted, with freedom for rotation, upon a stud 12 rearwardly projecting from a two-part rear movement-plate 13. Connected to the said drum by means of a transverse screw 14 and lying in the groove 11 thereof, 50 is a flexible pull-cord in the form of a ribbon 15 of spring-steel, having its free end extending outward through a bushing 16 in the lower side of the periphery of the clock-case 17 and provided at its extreme end with 55 a pull-button 18.

The winding-drum 10 is formed in its forward face with an annular recess 19 which receives a ratchet-wheel 20 provided with a forwardly-extending integral sleeve 21 rotating upon the stud 12, before referred to, and serving to couple a gear-wheel 22 to the said ratchet-wheel.

Engaging with the peripheral teeth of the ratchet-wheel 20 is a pawl 23 located in the recess 19 in the winding-drum 10 and pivotally secured to the latter by means of a stud 24. A spring-wire click-spring 25 of usual form is mounted upon the drum 10 in the recess 19 thereof by means of a stud 26 70 and exerts a constant effort to maintain the pawl 23 in yielding engagement with the teeth of the ratchet-wheel 20.

The gear-wheel 22 forms part of a winding-train and meshes into a gear-wheel 27 75 mounted with freedom for rotation upon a stud 28 rearwardly projecting from the rear movement-plate 13 and, in turn, meshes into and drives a gear-wheel 29 staked upon the rear end of a collect 30 extending through 80 and bearing in the rear movement-plate 13 and having staked to its forward end a cup-shaped spring-barrel 31.

The spring-barrel above referred to houses a spiral time-train driving-spring 32, the outer end of which is coupled to the flange 33 thereof by means of a pin 34. The inner end of the spiral driving-spring 32 is coupled in the usual manner by means of a pin 34^a to an arbor 35 having the main-wheel 36 of the 85 90

time-train staked upon its forward end. The rear end of the arbor 32 is reduced in diameter to form a trunnion 37 bearing in the collet 30 and similarly, the forward end of the said arbor is reduced in diameter to form a trunnion 38 bearing in the front movement-plate 39 of the clock.

10 The gear-wheel 29 above referred to and hence the spring-barrel 31 is prevented from turning clockwise (as viewed in Fig. 4) by means of a pawl 29^a yieldingly held in engagement with the teeth of the said wheel by means of a spring 29^b.

15 The main-wheel 36 forms a feature of a time-train which may be of any approved construction, but which, as herein shown, also comprises a pinion 40 driven by the said main-wheel 36 and mounted upon an arbor 41 carrying a gear-wheel 42 meshing into a pinion 43 mounted upon the center arbor 44 of the clock. The said center arbor also carries a center-wheel 45 meshing with a pinion 46 upon an arbor 47 which carries a gear-wheel 48.

20 25 The gear-wheel 48 meshes and drives a pinion 49 upon an arbor 50 carrying a gear-wheel 51 meshing into a pinion 52 staked upon an escapement-wheel arbor 53 of the clock. The arbor 53 carries an escapement-wheel 54 which imparts rocking movement, in the usual manner of escapement-mechanism, to an escapement-lever 55, in turn imparting oscillatory movement to a balance-wheel 56.

30 35 From the foregoing, it will be seen that when a downward draft is exerted upon the pull-button 18 and hence upon the outer end of the flexible ribbon 15, the drum 10 will be turned counter-clockwise, as viewed in Fig. 2, and the latter, through the intermediary of the pawl 23, ratchet-wheel 20 and gear-wheels 22, 27 and 29, will effect the turning of the spring-barrel 31 and hence the winding of the driving-spring 32 of the time-train.

40 45 For the purpose of reversely turning the drum 10 in order to return the pull-button 18 to its normal position, in which it is shown by full lines in Fig. 1, after the same has been pulled downward to effect the winding of the clock, as above described, I provide the said drum in its rear face with a concentric recess 57 in which is installed a spiral return-spring 58 having its outer end secured by means of a pin 59 to the wall of the said recess and having its inner end coupled by means of a pin 60 to the stationary stud 12 upon which the said drum rotates.

50 55 The said return-spring 58 is retained in the recess 57 of the drum 10 by means of a cover-plate 61 snapped into an annular groove 62 formed in the said drum immediately to the rear of the recess 57 therein, and 60 65 retained in place by a pin 63 extending

diametrically through the rear end of the stud 12.

60 By means of my invention, a clock may be conveniently and rapidly wound when desired by simply drawing upon the pull-button 18 and is particularly advantageous for use in situations where rotary winding devices upon the rear of the clock would be inconvenient to reach, such as is the case when clocks are mounted upon the instrument board of 65 automobiles.

70 While I have herein shown and described a flexible steel ribbon for winding the clock, I wish to have it understood that I do not limit myself to the same, since obviously a 80 cord, a cable, chain, etc., may be employed to replace the same. In the appended claims, I have for purposes of convenience employed the term "pull-cord" and wish to have it understood that by use of that term, I desire 85 to include the ribbon 15 or an equivalent flexible member.

75 It will be understood by those skilled in the art that my invention may assume varied physical forms without departing from my 90 inventive concept and I, therefore, do not limit myself to the specific embodiment herein chosen for illustration, but only as indicated in the appended claims.

95 I claim:

1. In a clock, the combination with a time-train and a driving spring therefor, of a winding-member provided with means for connecting it with said driving spring to wind the same, said winding-member including a drum carrying a pull-cord whereby rotation may be imparted to it to wind said spring as said cord is unwound from said drum, said drum provided with a recess housing a return-spring, said return-spring connected at its opposite ends with said drum and with a fixed part and adapted to be wound when said drum is rotated by said cord and to rotate said drum to rewind said cord when said cord is released. 105

110 2. In a clock, the combination with a time-train and a driving spring therefor, of a winding-member provided with pawl and ratchet means for connecting it with said driving spring to wind the same, said winding-member including a drum carrying a pull-cord whereby rotation may be imparted to it to wind said spring as said cord is unwound from said drum, said drum provided at one face with a recess housing a return-spring and at its other face with a recess to receive said pawl and ratchet means, said return-spring connected at its opposite ends with said drum and with a fixed part and adapted to be wound when said drum is rotated by said cord and to rotate said drum to rewind said cord when said cord is released. 115

120 3. In a clock, the combination with a time-train and a driving-spring therefor, of a fixed bearing-stud, a winding-member rotata- 125

bly mounted upon said stud and provided with means for connecting it with said driving-spring, a pull-cord carried by said winding-member and adapted to impart rotation thereto to wind said driving-spring as said cord is unwound from said winding-member, and a return spring housed within said winding-member and having its ends connected therewith and with said stud respectively, said return-spring adapted to be wound when said winding-member is rotated by pulling said cord and to reversely rotate said winding-member to rewind said cord when the cord is released.

In testimony whereof, I have signed this specification.

JACOB F. LANGBEIN.
